[57] CLAIM

The ornamental design for collapsible saw horse or the like, substantially as shown and described.

DESCRIPTION

FIG. 1 is a top plan view of the collapsible saw horse or the like in accord with my new design, the design being shown in its collapsed position;

FIG. 2 is a front elevational view thereof;

FIG. 3 is a left end elevational view thereof;

FIG. 4 is a right end elevational view thereof;

FIG. 5 is a bottom plan view thereof;

FIG. 6 is a partial back elevational view thereof;

FIG. 7 is an enlarged top plan view thereof with the bolt and thumb nut removed from FIG. 1 and the bolt inserted into aligned vertical openings to lock the design in a 45° angular position; and

FIG. 8 is a view similar to FIG. 7, but showing the design in a 90° angular position.
